UNITED STATES PATENT OFFICE

1,990,824

AIR NOZZLE FOR FLAT-SPRAYING
APPLIANCESEric Gustafsson, Chicago, Ill., assignor to Binks
Manufacturing Company, Chicago, Ill., a cor-
poration of Delaware

Application April 16, 1934, Serial No. 720,748

8 Claims. (Cl. 299—140.1)

My invention relates to the class of flat-spraying appliances which are constructed for projecting a composite stream composed of coating material commingled with and partly atomized by air, and for impacting two opposed and forwardly converging jets of air against this composite stream to complete the needed atomization of the material and to flatten the resulting spray.

10 In the conventional spray guns, as commonly used for spray coating materials on automobile bodies, furniture and the like, the material is initially projected in a stream of cylindrical section and also is initially housed by a tube of air which merges with and partly atomizes the material, this projected tube of air being initially a hollow cylinder having a uniform thickness throughout its circumference.

When the material which is to be sprayed is 20 of the nonhomogeneous class in which finely divided particles of heavy materials (such as a vitreous enamel) are intermingled with and carried by a liquid of considerably lower specific gravity (such as a pyroxylin lacquer) and which 25 liquid offers considerable resistance to a change in the cross-section of the projected stream of material, the flattening of the spray to the usually desired section of a highly elongated ellipse or rectangle requires the air of the two converging 30 air jets to be projected at such pressure that this spray-flattening air will flick an objectionably large part of the heavy constituent of the material out of the carrier liquid, thereby causing such an amount of "off spray" as to require 35 considerable hand labor for its elimination in the coating.

This difficulty can readily be overcome (after the manner disclosed in United States Patent #1,897,173, issued February 14, 1933 on the joint 40 application of Robert Long and myself) by thickening the wall of the projected tube of air along the two sides of the material stream which are at right angles to the common plane of the axes of the two converging air jets, so that the 45 increased volume of air supplied along the said two sides of the material stream will first flatten the aforesaid composite stream in a direction at right angles to that in which the converging air jets thereafter flatten the spray. In practice, 50 the air nozzle of the just mentioned patent has proven satisfactory only when the material is to be sprayed at a fairly moderate rate per minute in proportion to the diameter of the initially emitted stream of material.

55 However, when the rate at which the material

is emitted is considerably increased, so as to meet the demand of automobile manufacturers for a speedier spraying of a coating of given thickness over a given area, the supply of air per minute for the air tube must be correspondingly increased, as also that of the air for the converging air jets, so that the cost of the needed compressed air rises undesirably. Moreover, even for spraying at relatively moderate rate, the step of first deforming the material stream to an elliptical section having its longer axis in the same plane with the axes of the (spray-flattening) converging air jets necessarily requires the use of considerable air energy for this stream-section deformation.

To reduce this consumption of compressed air, it has also been proposed that two auxiliary air jets be projected respectively contiguous to the two sides of the composite material stream against which the (spray-flattening) converging air jets are directed, several types of spray-appliance heads for this purpose being disclosed in the copending application #694,796 of Eric Gustafsson, filed October 23, 1933 and assigned to the same assignee as my present application. However, with the just recited disposition of the two auxiliary air jets, these auxiliary jets respectively commingle with the two converging air jets, so as to concentrate the effect of the atomization near the common plane of all of the said jets. Consequently, when the rate of air supply for the auxiliary air jets is increased to correspond to the rate at which the material is projected for quite rapid spraying, a considerable portion of the heavier ingredient of the material is flicked out of the liquid carrier to form an "off spray," and the total air consumption (in proportion to the material consumption) also rises undesirably.

My present invention aims to overcome the heretofore recited objections, as particularly encountered when spraying material at a higher rate per minute than has previously been customary, by providing an arrangement of air ports which will decidedly reduce the consumption of compressed air in comparison to the volume of the sprayed material, while also preventing the production of an undesirable amount of "off spray" and affording such a distribution of the particles of the sprayed material that these particles will readily flow into one another in the resulting coating.

Generally speaking, I accomplish these objects by combining the operating principles of the air nozzles both the said Long and Gustafsson Pat- 55

ent #1,897,173 and of my said application #694,796; by so reportioning the emission of the air streams which commingle with the projected material stream before the impact of the 5 converging (spray-flattening) air jets on the resulting composite stream, so as to increase the diameter of this stream both along the common plane of the axis of the converging air jets and along a plane axial of the said composite stream 10 and at right angles to the aforesaid stream.

More particularly, I accomplish my above recited objects by constructing a spray-appliance air nozzle in which the provisions, auxiliary to the conventional projecting of a cylindrical tube 15 of air around the initially projected material stream, for projecting air into merging relation with this material stream are so arranged that the auxiliary air will form two longitudinal air ribs projecting from the material stream and 20 against which the converging air jets respectively impact; and also will form two other longitudinal air ribs projecting from the material stream with the axes of the last named air ribs disposed in a plane at right angles to the common 25 plane of the axes of the converging air jets, and with the last named air ribs of greater spread (circumferentially of the material stream) and less thickness radially of that stream than the first named air ribs.

Furthermore, my invention is based on my discovering, as the result of a long series of experiments and observations, that by the here disclosed projecting of auxiliary air along four sides of the projected material stream, and the here disclosed proportioning and directing of the auxiliary air, I enable the various portions of this auxiliary air to cooperate in such a manner that the total amount of compressed air required for producing a spray of given atomization from a material stream projected at a given pressure is much less than the amount of compressed air which I have found to be required for the same purposes with older types of spray appliances.

In the accompanying drawing,

Fig. 1 is a central and vertical section through the forward parts of a spray gun constructed for operating according to my invention.

Fig. 2 is a front elevation of the same.

Fig. 3 is an enlargement of a part of Fig. 2.

Fig. 4 is a perspective view showing the streams projected by the spray head of Fig. 1, when no spray-flattening air is emitted from the side air ports.

Fig. 5 is a similar perspective view, taken when air is also issuing from the side air ports.

Fig. 6 is an enlarged approximate cross-section of the composite stream shown in Fig. 4, taken along the line 6-6 of Fig. 4.

Fig. 7 is an enlarged front elevation of the central portion of an alternative form of my air nozzle, namely one in which two separate air ports are substituted for the enlargements of the bore of the central air port shown in 60 Fig. 3.

Fig. 8 is a fragmentary sectional view taken on line 8-8 of Fig. 3.

Illustrative of my invention, the drawing shows this as applied to a spray appliance of the 70 Svend Bramsen Patent #1,910,673 of May 23, 1933 on a Spray gun.

In the portions of a thus modified spray gun shown in Fig. 1, the gun body (or barrel) 1 has two longitudinal fluid passages, one being a material passage 2 into the forward end of which

the rear end of a material nozzle 3 is threaded, and the other being a compressed-air supply passage 4. The forward end of the gun body 1 is formed to afford an air chamber into which the air passage 4 opens, and from which chamber air can issue (through an annular port 5 in the forward wall of this air chamber) so as to flow around and alongside the material nozzle 3.

Butting against the front end of the gun body and freely surrounding a part of the material nozzle is a partitioning tube 6 which spaces the air nozzle of the appliance forwardly from the gun body and which has an annular baffle web 7 extending radially outwardly from it. As here shown, the air nozzle N is of a conventional type, shaped generally as a rearwardly open cup which has its rearward portion sleeved on the forward part of the tube 6, and which has forwardly projecting horns H at diametrically opposite sides of a central flat-faced frontal portion 9. A retaining ring R supports the air nozzle from the gun body and also clamps the said tube between the gun body and the air nozzle.

The forward wall of the said air chamber C also has a port 8 which connects the air passage 4 with the annular space between the partitioning tube 6 and the retaining ring R. This port 8 is controlled by an air valve 10, and the air nozzle has two air passages 11 extending respectively forwardly into the horns H. These two passages 11 open through forwardly converging side ports 12 from which the spray-flattening side air jets S (Fig. 5) are emitted, the supply of air to the two side ports being substantially equalized by the baffle web 7 which has its periphery spaced from the bore of retaining ring R by a minor fraction of the radial width of the said web so as to compel some of the air to flow around the partitioning tube 6 after the air has been admitted behind this baffle through the valve-controlled port 8.

Air also flows forwardly from the air chamber C through the body-front port 5, the space between the partitioning tube 6 and the material nozzle 3, and through longitudinal ports 13 in the air nozzle (as indicated by the lower set of arrows in Fig. 1) into the forward central portion of the cup-shaped part of the air nozzle, so as to issue through the commonly provided central frontal air port around the exteriorly cylindrical tip 15 of the material nozzle. In the air nozzle of the said Bramsen patent, which is owned by the assignee of my present application, this central air port was circular and of cylindrical bore, as shown at 14 in Fig. 7, and was the only forwardly opening port in the central portion of the air nozzle.

To adapt the heretofore described prior construction to non-homogeneous materials now widely used for coatings and to reduce the amount of compressed air needed in proportion to the sprayed material, I augment the previously employed annular central air port by either of the two provisions respectively shown in Figs. 3 and 7, namely by arrangements for projecting an increased amount of air longitudinally alongside and in merging relation to the material at four sides of this stream, with this additional air suitably proportioned to the diameter of the side air ports 12.

In the embodiment of Figs. 2 and 3, the central air port 14 has two diametrically opposite bore enlargements 15, each having substantially semi-cylindrical interior surface the axis of

which is in a plane T axial of the enlarged parts 5 of the port 14 (and hence coaxial with the tip 16 of the material nozzle) and at right angles to the common plane P of the axes J (Fig. 1) of the side air ports 12. Each of these bore enlargements also preferably has its axis sloping rearwardly away from the axis A of the liquid nozzle, as in Fig. 8, so that each bore enlargement tapers forwardly at an angle of not 10 exceeding approximately 10 degrees.

Each such bore enlargement desirably extends for approximately one quarter of the circumference of the central air port, and has its central and maximum width (radially of the said port) 15 a minor fraction of its said circumferential spread, the general proportioning of the central air port being desirably such that the area of each of these bore enlargements is not greater than the area of one of the side air ports 12.

By thus using a taper angle of a maximum only about half as great as that shown for the allied, but differently positioned, bore enlargements in the air nozzle of the Long and Gustafsson Patent #1,897,173, I cause each bore 20 enlargement to function partly (but less intensely) after the manner of the just named patent in tending to change the cross-section of the material stream, and partly (after the manner of the separately formed cylindrical 25 ports of my own copending application #694-796) to form a longitudinal air rib along the material stream.

To co-operate with these enlargements of the central bore of the air nozzle, I also provide 30 two auxiliary and preferably cylindrical air ports 20 of cylindrical bore, which ports have their axes parallel to and equally spaced from the general axis of the air nozzle and at a sufficiently short spacing so that the air emitted 35 from the said auxiliary ports 20 will merge with the air projected through the previously described central air port and form longitudinal air ribs at opposite sides of the material stream. Each of these auxiliary air ports 20 is of smaller 40 area than one of the said bore enlargements 15 of the central air port, and has its axis in a common plane P (Fig. 3) with the axes J (Fig. 1) of the side air ports 12, namely a plane diametric of the material discharge port 16 and 45 of the central air port of the air nozzle.

When my thus constructed spray appliance 50 is in use, with a stream of material issuing from the discharge port 16 of the material nozzle, and with air issuing around the tip of that nozzle, through the central air port, but with the valve 55 closed so that no air is issuing from the side ports 12, the observed operation is substantially as pictured in Fig. 4, namely as follows:

The contour of the four-lobed tubular stream 60 of air issuing from the central air port corresponds initially to that shown for this port in Fig. 3, and if the auxiliary ports 20 were not present, the increased amount of air issuing through the enlargements 15 of the central air 65 port would act (after the manner disclosed in the Long and Gustafsson Patent #1,897,173) to change the cross-section of the material stream to an elliptical section having its longer axis in the common plane P with axes of the side ports 12.

However, the two jets of air B which issue 70 from the auxiliary air ports 20 quickly join the air issuing from the central air port, as shown in Fig. 4, and when the several air ports are proportioned as previously described, these auxiliary air jets prevent a changing of the general

cross-section of the material stream to a simple elliptical section. Consequently, the speedy commingling of air with the projected liquid material makes the resulting composite stream of approximately the cross-section (in the transverse plane along the line 6-6 of Fig. 4) which is shown on an enlarged scale in Fig. 6, 10 namely with two diametrically opposite lobes C^a of relatively small thickness (radially of the composite stream) both centered along the plane T of Fig. 3, and with relatively narrower lobes C^b of considerably greater radial thickness diametrically opposite each other and each centered along the plane P of the same figure.

When the valve 10 is then opened so that forwardly converging air jets S issue also from the side air ports 12 in the horns of the air nozzle, each of these side air jets impinges against one of the ribs formed on the composite material stream by the lobes C^b of Fig. 6, so as to prevent a splitting or undue indenting of this stream, while the other two ribs (corresponding to the lobes C^a) partly compensate for this by already widening the composite stream along the plane T (Fig. 3) in which the spray is to 20 be flattened. Consequently, when the valve 10 is only partially opened, so as to flatten the spray to a still decidedly elliptical section, the projected fluid portions adjacent to the forward end of the spray-gun appear approximately as 25 shown in Fig. 5.

By thus distributing the air, which commingles with the material stream to a considerable extent before the side air jets impinge on the resulting composite fluid stream, I have 30 found that I can secure a uniformly fine atomizing of the material with any desired extent of the flattening of the spray (which is controlled by adjusting the valve 10) with a considerably 35 smaller total consumption of compressed air 40 than that heretofore needed for the same purpose. For example, with one of the coating materials now commonly used on automobiles, namely the Du Pont "De Luxe" lacquer, I have 45 reduced the air consumption (for spraying a given quantity of material) from 35 cubic feet per minute to 25.

I have also found that my new air nozzle will 50 permit the rate of material spraying to be increased without increasing the air consumption in the same ratio, so that my present invention effects a large saving of air when the spraying is done at high speeds so as to increase the surface area which can be sprayed per hour by a single spray gun.

In addition, I have found that a spray gun 55 constructed as here disclosed will effect such a decided saving of air, and permit such a reduction of the spraying time, with widely varying materials, including those having heavy pig- 60 ments (such as vitreous enamels), socalled synthetic lacquers and enamels, and asphalt emulsions.

Owing to my supplying an increased quantity 65 of air along four sides of the projected stream of materials, I have also found that such materials are atomized to a more uniform extent than by the spray appliances heretofore employed for the same purpose, consequently the resulting coating is so much more uniform as 70 to require less "sanding" (rubbing down with sand-paper) before another coating is applied, and in many cases a reduced number of layers of coating material are adequate for securing a 75 really smooth surface.

Moreover, I have found that my here presented air nozzle also reduces the consumption of air and improves the uniformity of the coating when the material is projected under relatively low pressure, as for example from so-called siphon-cup spray appliances, where the material pressure may be only about 5 pounds.

However, while I have heretofore described the use of lobe-like enlargements of the central 10 port of the air nozzle for affording the additional air along the plane T of Fig. 6, I do not wish to be limited in this respect, as I have obtained approximately the same advantages by employing two supplemental air ports in substitution for the said bore enlargements. Thus, 15 Fig. 7 shows the central frontal portion of an air nozzle with the central air port 14 circular, and with two supplemental circular air ports 21 having their axes equally spaced from the axis of this central port and in the plane T (diametric of the said port) at right angles to the 20 diametric plane P in which the axes J of the converging side air jets of this nozzle extend.

In this alternative form of my air nozzle, I 25 have found that the supplemental air ports 21 are preferably of cylindrical bore, of a diameter approximately one-third greater than that of the auxiliary ports 20 (which would be in the same proportion to the size of the side air ports 30 12 as in Figs. 1 to 3), and with the axis of each supplemental air port spaced by approximately its own diameter from the circular central air port. With this type, it will be noted that the area of each supplemental air port, port 21 is 35 intermediate that of each auxiliary air port 20 and of the area of one of the counterpart side air ports 12. It will also be noted that diameter of each of the larger two air ports adjacent to the central air port is considerably smaller than 40 the diameter of the material discharge port, this difference in size being required in order that the projected four auxiliary streams of air will produce four separate projecting ribs (shown at A and B in Fig. 4) instead of merging into one 45 another.

Moreover, while I have described my here presented air nozzle as used on a particular type of spray gun, it is to be understood that this is merely illustrative of its use, and that many 50 changes might be made without departing either from the spirit of my invention or from the appended claims.

I claim as my invention:

1. In an appliance for producing a flattened spray, a material nozzle having a discharge tip through which material is projected forwardly; and an air nozzle having two side ports, respectively at opposite sides of the axis of the said tip, for projecting jets of air along forwardly converging jet axes lying in a common plane with the said tip axes; the air nozzle also being provided with a group of ports for projecting air generally parallel to the tip axes and around and in merging relation to the initially projected stream of material; the said ports being so proportioned and disposed that air projected through them will form two pairs of diametrically opposite ribs on the composite stream formed by the intermingling of air with the projected stream, with the ribs of one pair respectively facing the two side air ports, and with each of the other ribs equally spaced from the aforesaid two ribs.

2. A spray appliance as per claim 1, in which 75 the ports of the said group are so proportioned

and arranged that the ribs facing the two side ports are of greater thickness, radially of the composite stream, than the other two ribs.

3. A spray appliance as per claim 1, in which 5 the ports comprising the said group have their mouth ends substantially in a common plane at right angles to the axis of the discharge tip of the material nozzle.

4. In an appliance for producing a flattened spray, a material projecting nozzle having a forwardly open tip; an air nozzle presenting two side ports, respectively at opposite sides of the axis of the said tip, for projecting jets of air along two forwardly converging jet axes lying in a common plane with the said axis; the air nozzle having in its central portion a group of ports for projecting air generally coparallel to the said tip axis around and in merging relation to the initially projected stream of material but with a smaller proportion of the air projected 20 along the two sides of the said stream which face the side air ports than along the other two sides of the stream which are in a second plane diametric of the said tip and at right angles to the aforesaid plane, and for projecting auxiliary 25 air in less speedily merging relation along the first named two sides of the stream.

5. In an appliance for producing a flattened spray, a material nozzle having a tip of cylindrical contour; and an air nozzle having a central air port coaxial with and freely housing the said tip, and having two counterpart side air ports for projecting air from opposite sides of the axis of the said tip along two forwardly converging jet axes lying in a plane diametric of the said axis; the central air port having a bore of substantially elliptical section with the minor axis of the ellipse in the said plane; the air nozzle also having two counterpart auxiliary ports coparallel with the central air port and respectively at opposite sides of and equally spaced from the said central air port, the axes of the said auxiliary air ports lying in the said plane and the area of each auxiliary air port being a minor fraction of the area of one of the side 45 air ports.

6. A spray appliance as per claim 5, in which the substantially elliptical section of the bore of the central air port is such that the increase in area of each of the two halves of that port at 50 opposite sides of the said plane, at the mouth end of the port, is intermediate between the area of one of the side ports and that of one of the auxiliary air ports.

7. In a spray appliance in which generally 55 liquid material is projected through the tip of a material nozzle, an air nozzle having a central air port coaxial with and freely surrounding the said tip of the said material nozzle and having two side air ports for projecting converging 60 jets of air along two axes disposed in a plane diametric of the said nozzle tip and intersecting on the axis of the nozzle tip; the air nozzle also having port provisions for projecting air forwardly contiguous to the stream of material projected by the material nozzle, the said port provisions being formed so that the air afforded by them will initially entirely surround the projected stream of material and will transform the said projected stream, before the impact of the 70 said jets against the stream, to a partially aerated stream having a four-lobed cross-section having two opposite lobes extending symmetrically across the said plane and the other two lobes of less radial depth extending across a 75

second plane diametric of the said nozzle tip and at right-angles to the aforesaid plane.

8. In a spray appliance in which generally liquid material is projected through the tip of a material nozzle, an air nozzle having a central air port coaxial with and freely surrounding the said tip of the said material nozzle and having two counterpart side air ports for projecting converging jets of air toward a common point 10 on the axis of the projected stream of material; the bore of the central air port being circular except for two diametrically opposite and counterpart bore enlargements each of a spread approximating one quarter of the circumference of the said bore and of a maximum depth in a plane diametric of the said axes and at right angles to a common plane including the axes

of the said side ports, the said maximum depth of each bore enlargement being a minor fraction of the circumferential spread of the said enlargement; the air nozzle also having two counterpart auxiliary air ports equally spaced from the axis of the central air port and each spaced from the bore of the central air port by a distance not materially greater than the diameter of one of the auxiliary air ports, each of the said auxiliary ports being of smaller cross-sectional area than one of the said recesses; the said auxiliary air ports being at opposite sides of the central air port and having their axes in the said common plane, and the area of each bore enlargement being less than that of one of 15 the side air ports.

ERIC GUSTAFSSON.
